BRAKE BLEEDER ADAPTER

Leo C. Bogaerts, Antioch, Ill., assignor to Ammco Tools, Inc., a corporation of Illinois

Filed Jan. 2, 1968, Ser. No. 10,018

Term of patent 14 years

Int. Cl. D8—02

U.S. Cl. D54—13

FIGURE 1 is a perspective view of a brake bleeder adapter showing my new design; the broken line showing of a brake cylinder being for illustrative purposes only;

FIGURE 2 is a top plan of the device of FIG. 1;

FIGURE 3 is a left side elevation of the device of FIG. 1;

FIGURE 4 is a right side elevation of the device of FIG. 1;

FIGURE 5 is a bottom view of the device of FIG. 1 and

FIGURE 6 is a bottom plan view of a modified form of the brake bleeder adapter, wherein the only difference resides in the specific configuration, as indicated.

The fragmentary showing of the chain element in FIGS.

2 through 6, inclusive, is for convenience of illustration.

I claim:

The ornamental design for a brake bleeder adapter, substantially as shown and described.
